UNITED STATES PATENT OFFICE.

GEORGE HOWARD HILDER, OF NEW YORK, N. Y.

DESIGN FOR A TOY.

43,707.

Specification for Design.

Patented Mar. 11, 1913.

Application filed August 29, 1912. Serial No. 717,792. Term of patent 3½ years.

To all whom it may concern:

Be it known that I, GEORGE HOWARD HILDER, a citizen of the United States, residing at New York, in the county of New York and State of New York, have invented a new, original, and ornamental Design for Toys; and I do hereby declare the following to be a full, clear, and exact description of the same, reference being had to the accompanying drawing, forming a part thereof.

The drawing shows my design for a toy in elevation.

I claim—

The ornamental design for a toy as shown. In testimony whereof I hereunto affix my signature, in presence of two witnesses.

GEORGE HOWARD HILDER.

Witnesses:

GEORGE L. THOM,
